UNITED STATES PATENT OFFICE.

PHILIP CHARLES LAWLESS, OF HAMPSTEAD, ENGLAND.

INTERNAL-COMBUSTION ENGINE.

No. 876,003.

Specification of Letters Patent.

Patented Jan. 7, 1908.

Application filed October 25, 1905. Serial No. 284,404.

To all whom it may concern:

Be it known that I, PHILIP CHARLES LAWLESS, subject of the King of Great Britain, residing at No. 50 Parliament Hill, 5 Hampstead, in the county of London, England, have invented new and useful Improvements in and Relating to Internal-Combustion Engines, of which the following is a specification.

10 This invention relates to an improved process of operation in internal combustion engines and means for carrying it into effect whereby the quantity of air admitted, to form a portion of the working charge, may, 15 relatively to the combustible portion, be greatly increased and very largely varied, as compared with what has hitherto been possible.

According to this invention the combustible fluid, mixed with a sufficient quantity 20 of air to most effectually promote ignition, is admitted to a working chamber and, separated therefrom, an additional quantity of air is also admitted to the same chamber.

25 After admission, both quantities are compressed to approximately the same pressure and then the combustible mixture is fired, causing, by its expansion, a further compression of the separated air, followed by a 30 transference of such air into the space containing the burned or burning combustible mixture and its intimate mixture therewith, the combined charge being then caused to do work by expansion.

35 Instead of the separated quantity consisting of air alone, it may, under some circumstances, comprise another fluid, or other fluids, combustible or otherwise, but in general it will be air alone or chiefly air, and 40 in the succeeding description it will be referred to as if it consisted entirely of air.

45 Superposed on the cycle of operations as above described means may be provided for supplying the charge to the working chamber under a pressure in excess of the atmosphere and thereby increasing the work capacity of the engine.

50 A method of construction and operation will be described by way of example, but it is to be understood that the supply of the charge to the working chamber under compression is not an essential feature of this invention, and it is to be further understood that other means may be adapted for supplying the working charge under compression, alternately to those described herein.

From a sequence of operations as above enumerated many advantageous results are derivable, as for example:—While always providing a richness of mixture to insure ignition and complete combustion, the added air can be increased almost without limitation, by which means:—(1) The power of the engine can be varied within wide limits, and regularity of motion maintained at low power, each charge being effective though small. (2) The temperature of the cylinder can be reduced to limits which conduce to safety, durability and maximum efficiency. (3) For the external abstraction of heat from the exterior surface of the cylinder, is substituted an internal abstraction by the added air, and its utilization in work production, whereby the efficiency of the engine will be largely increased, and the complications involved in the provision of externally applied cooling fluid will be avoided.

One method of obtaining the desired results is by the provision, at the closed end of the cylinder of an internal combustion engine, of an additional piston which, by the action of a spring or weight or by fluid pressure, tends to recede from the closed end of the cylinder and approach the working piston of the engine and alternately to be thrust away by fluid pressure from the working piston. This additional piston will, in this specification, be referred to as the "serving-piston" and be so distinguished from the "working-piston" which is mechanically connected to the engine crank-shaft.

The accompanying drawing shows, as a representative example, a form of construction of a motor whereby the process above described can be carried into effect, together with means for supplying the working charge to the cylinder under pressure in excess of the atmosphere.

In this drawing: Figure 1 is a plan of the 100 motor. Fig. 2 is an elevation as viewed in a direction at right angles to the motor shaft. Fig. 3 is a conventional vertical section of the motor the upper portion of which is taken along vertical planes whose traces are indicated in Fig. 1 by 3^0-3 , $3-3^1$, 3^1-3^2 , and 3^2-3^3 these planes being developed on to the single plane of the figure. Fig. 4 situated below Fig. 3 is a vertical section of the lower portion of the motor taken along the planes 110 whose traces are indicated in Fig. 2 by $4-4$.

In this drawing, a is the cylinder which is

fitted with a plunger-shaped working-piston *b*, of ordinary construction, which is coupled by a connecting rod *c* to a pin which is secured at its ends to two disks *d*, *d'* which latter, are themselves secured to the motor shaft *d*. The crank-chamber *e* is inclosed in an air-tight manner so that on the up-stroke of the working-piston air can be drawn from the atmosphere and compressed on the down-stroke. Fitting in the same cylinder *a*, above the working-piston, is the above mentioned serving-piston *f*, which is secured to a rod *f'* which works fluid-tight through the stuffing-box *g* in the cylinder cover *a'*. A disk *f''* secured to the end of the rod serves to limit the downward movement of the serving-piston and arrest it, without shock by a cushion of air confined in a cup formed in the gland of the stuffing box *g*.

When the serving-piston *f* is at the upper end of its stroke, in contact with the cylinder cover *a'*, a helical spring *h* is compressed and the compressive force tends to thrust the serving-piston a small distance away from the upper end of the cylinder. The serving-piston is fitted with a spring ring *f'''* in its upper portion so as to make a fluid-tight joint with the cylinder, but the diameter of the lower portion of the piston *f* is made somewhat less than that of the cylinder leaving a narrow annular space between them. In the upper end of the cylinder *a* longitudinal or slightly helical grooves *a''* are cut, whereby, when the serving-piston is at the upper end of its stroke, a passage from one side of the serving-piston to the other side is provided.

To the space *i* between the two pistons a mixture of combustible fluid and air is admitted from a passage *i'* and through a spring closed non-return valve *j*, the products of combustion being subsequently evacuated through the same passage *i'* on the mechanical opening of an exhaust valve *k*. To the space *m*, above the serving-piston, air is forced at a pressure in excess of the atmosphere. This air is drawn into the crank-chamber *e* through the valve *o* on the up-stroke of the working-piston *b* and, on the downstroke, this air is compressed and forced through a non-return valve *o'* into a passage *o''* leading beneath a spring-closed valve *n*. At a suitable period of the cycle the valve *n* is lifted by a cam permitting the compressed air to flow to the upper side of the serving-piston. There is, in addition, a spring closed valve *p* which is mechanically opened inwards, periodically, to allow of the escape of air from the space *m* under special circumstances to be presently described.

q is the firing plug which serves to ignite the fluid at the appropriate time, in the usual way.

The operations of the engine will be performed as follows: The drawing shows the serving-piston *f* in contact with the cylinder

end and the working-piston at the upper extremity of its stroke. These will be approximately the positions of the two pistons immediately after firing the combustible charge, as will be presently explained. At 70 this moment the spaces *i* and *i'* will be occupied by the burned or burning charge at its maximum pressure and, on the descent of the working-piston *b*, the charge will expand and do work at gradually diminishing pressure. When the piston *b* has nearly reached the lower end of its stroke it is arranged for the exhaust valve *k* to be lifted by a cam in the manner usual in internal combustion engines. At this instant, if not earlier, the 80 spring *h* will have thrust the serving-piston *f* away from the cylinder-end sufficiently to cover the lower ends of the grooves *a''* and close the communication between the spaces *m* and *i* on the two sides of the serving-piston. The serving-piston will move a small distance further by reason of the expansion of the fluid contained in the passage *m'* and will attain a position at which it will be able to make actual or approximate contact with the working-piston when it returns to the upper end of its stroke. During the completion of the down-stroke of the working piston and also during the return stroke, the exhaust valve *k* will be retained open and during the interval the free evacuation of the burned gas will be permitted. The actual or proximate meeting of the pistons at the end of the upstroke of the working-piston will also promote a very effectual evacuation. 95 On the next downstroke of the working-piston a mixture of combustible fluid and air will be drawn into the cylinder between the two pistons through the admission valve *j*. During this movement the serving-piston 105 will be able to follow the working-piston only a little way as it would entail an expansion of the air in the space *m* to a pressure less than the atmosphere. Consequently, into the space *i*, there will be drawn a mixed charge of combustible fluid and air in volume not much less than the displacement volume of the working-piston. When the downstroke of the working-piston has been nearly completed it is arranged for the valve *n* to 110 be lifted by a cam whereby air under pressure will be admitted to the space *m* above the serving-piston; the serving-piston will thereby be forced downwards and compress the combustible charge in *i* to approximately 115 the same pressure as the air admitted to *m*. In this way, at the commencement of the next upstroke of the working-piston the cylinder will contain a quantity of combustible gas under pressure between the two 120 pistons and above the serving-piston there will be a quantity of additional air also under pressure. During the upstroke these two quantities will undergo compression, each to about the same intensity of pressure, 125 130

the serving-piston adapting its position to maintain a balance of the pressures on its two sides. When the upstroke is on the point of completion it is arranged for the 5 firing plug g to be rendered active and effect the ignition of the combustible charge in the spaces i and i' . The immediate increase of temperature which will follow will have the effect of causing an expansion of the burning 10 fluid, the consequent displacement of the serving-piston completing the compression of the charge of air in the space m . By the considerable pressure developed by the combustion the serving-piston will be displaced 15 sufficiently to uncover the ends of the grooves a^2 and place the space m in communication with the space i . There being less area above the serving-piston, for the fluid to act on, than beneath, by the amount of the sec- 20 tional area of the piston rod f^1 , the serving-piston will be forced entirely to the end of the cylinder and the air in the space m will be entirely transferred to the space i by flowing through the grooves a^2 and after- 25 wards through the narrow annular space between the body of the serving-piston and the surface of the cylinder whereby it will be directed to sweep with considerable velocity in close contact with the metal of the 30 cylinder which has just been exposed to the burning gases and thereby recover the heat which will have been temporarily absorbed by the metal. If at this time combustion has not been completed, the intimate mixing 35 of the warmed air with the burning gases will promote their very complete combustion. The transfer of air from m to i will take place at practically constant volume. The tendency to a diminution of pressure by 40 the abstraction of heat from the burning gases will be entirely compensated for by the tendency to an increase of pressure due to the reception of the same quantity of heat by the inflowing air and thus, although the 45 temperature will be reduced very much below the temperature of combustion, there will be no diminution of pressure. The working-stroke will now commence during which the highly compressed gas will ex- 50 pand and urge the working-piston. During this stroke so long as the pressure in the cylinder is sufficient to overpower the helical spring h , the serving-piston will be kept in contact with the cylinder cover. 55 In the event of a mis-fire the charge of air admitted to the space m will not be transferred to the space i and this will interfere with the reception of a full charge of combustible mixture to the space i on the next 60 intake because the serving-piston will follow the working-piston unduly far during this suction stroke. To provide for this contingency an additional spring-closed valve p which opens inwards to the passage m^1 may 65 be fitted, it being arranged for this valve to

be mechanically opened for a short period and permit the escape of the unused charge of air admitted to the space m . This valve may also be beneficial in starting the engine but its employment is not essential. The 70 valves k , n and p are mechanically opened by means of cams k^1 , n^1 and p^1 secured to a cam- 75 shaft r which is driven by a pair of one-to-two gear-wheels r^1 r^2 in the usual manner. Inter- 80 posed between cam k^1 and the stem of the valve k is a lever k^2 and a short separate stem k^3 . Similarly there is a lever n^2 and stem n^3 interposed between n^1 and n . The valve p is opened by the downward pull of the rod p^2 which connects the upper lever p^3 with the lower lever p^4 on which latter the cam p^1 85 operates.

I claim:

1. In an internal combustion engine, a cylinder, a working piston in said cylinder 85 mechanically connected with the crank shaft of the engine, means for supplying a charge of combustible mixture to the cylinder, means for supplying a charge of air to the cylinder, means separating the two charges, 90 and means for transferring the charge of air to the space occupied by the mixture immediately after ignition thereof.

2. In an internal combustion engine, a cylinder, a working piston in said cylinder 95 mechanically connected with the crank of the engine, a free serving piston in said cylinder, means for supplying a charge of combustible mixture to one side of the serving piston, means for supplying a charge of air to the 100 other side of the serving piston, and means for transferring the charge of air to the space occupied by the mixture immediately after ignition thereof.

3. In an internal combustion engine, a cylinder, a working piston in said cylinder 105 mechanically connected with the crank shaft of the engine, a free serving piston in said cylinder, means for supplying a charge of combustible mixture to the space between 110 the two pistons, means for supplying a charge of air to the space on the side of the serving piston remote from the working piston, and a channel in said cylinder adapted to place both sides of the serving piston in communica- 115 tion immediately after ignition of the mixture.

4. In an internal combustion engine, a cylinder, a working piston in said cylinder 120 mechanically connected with the crank shaft of the engine, a free serving piston in said cylinder, a piston rod connected with said serving piston and passing out of the cylinder, means for supplying a charge of combustible mixture to the space between the two 125 pistons means for supplying a charge of air to the space on the side of the serving piston remote from the working piston, and grooves in said cylinder adapted on ignition of the mixture and consequent displacement of the 130

serving piston, to place both sides thereof in communication.

5. In an internal combustion engine, a cylinder, a working piston in said cylinder mechanically connected with the crank shaft of the engine, a serving piston in said cylinder, a piston rod connected with said serving piston and passing out of the cylinder, means for supplying a charge of combustible 10 mixture to the space between the two pistons, an inclosed crank case, a valve controlled channel connecting the crank case and the space on the side of the serving piston remote

from the working piston, and grooves in said cylinder adapted on ignition of the mixture 15 and consequent displacement of the serving piston to place both sides thereof in communication.

In testimony whereof I have signed my name to this specification in the presence of 20 two subscribing witnesses.

PHILIP CHARLES LAWLESS.
